(57) **CLAIM**

The ornamental design for an adhesive strip, as shown and described.

DESCRIPTION

FIG. 1 is a perspective view showing the new design for an adhesive strip;

FIG. 2 is a top view thereof;

FIG. 3 is a bottom view thereof;

FIG. 4 is a front view thereof, a rear view being a mirror image thereof; and,

FIG. 5 is a left side view thereof, a right side view being a mirror image thereof.

The broken lines in the drawings are shown for illustrative purposes only and form no part of the claimed design.
